UNITED STATES PATENT OFFICE.

STEPHEN Q. HAYES AND CHARLES McL. MOSS, OF PITTSBURGH, PENNSYLVANIA,
ASSIGNORS TO WESTINGHOUSE ELECTRIC AND MANUFACTURING COMPANY, A
CORPORATION OF PENNSYLVANIA.

SWITCHING DEVICE.

1,227,434.

Specification of Letters Patent. Patented May 22, 1917.

Application filed May 1, 1913. Serial No. 764,845.

To all whom it may concern:

Be it known that we, STEPHEN Q. HAYES and CHARLES McL. Moss, citizens of the United States, and residents of Pittsburgh, 5 in the county of Allegheny and State of Pennsylvania, have invented a new and useful Improvement in Switching Devices, of which the following is a specification.

Our invention relates to switching devices and particularly to swinging-blade disconnecting switches.

The object of our invention is to provide a disconnecting switch of the pillar or post type which will thoroughly ground itself and both sides of a circuit breaker with which it is interlocked, when in full open position.

It frequently becomes necessary to repair oil circuit breakers, and, when repairs are being made, it is preferable to electrically isolate the breakers. In order to do this, it is desirable to have disconnecting switches on both sides of the breaker. It is also preferable to ground the terminals of the breaker when working on it. To thoroughly disconnect an oil circuit breaker from an electrical circuit and to so ground all terminals of the same as to insure safety for workmen is the object of our invention.

In our invention, we also provide means for automatically opening the electrical circuit on both sides of an oil circuit breaker when the circuit breaker itself opens. A more explicit description of our invention will be given in connection with the accompanying drawings.

Figure 1 is a view mainly in side elevation but partially in section, of apparatus embodying our invention. Fig. 2 is an end elevation of one pair of disconnecting switches. Fig. 3 is a diagrammatic view of a system embodying an application of our invention. Fig. 4 is a diagrammatic view of a set of switches when open and grounded.

As shown in the drawings, an electric generator 1 delivers power through conductors 2, disconnecting switches 4, 5 and 6, oil circuit breakers, 7, 8 and 9, and disconnecting switches 10, 11 and 12 to an electrical circuit 3. When it becomes necessary to electrically close circuit breakers 7, 8 and 9 or to operate the disconnecting switches 4, 5, 6, 10, 11 and 12, a rod 13 is

operated to transmit motion to a bell crank 55 lever 14 which, in turn, operates a rod 15 having attached to it a plurality of levers 16 that transmit their motion to a plurality of rods 17, the latter being arranged to operate blades 18 of disconnecting switches 4, 5, 6, 10, 11 and 12.

The contact members of the disconnecting switches 4, 5, 6, 10, 11 and 12 are supported by pillars 19 and 20 that comprise sets of insulators and are mounted in pairs 65 on opposite sides of frames 21, 22 and 23. Frames 21, 22 and 23 are supported by a main frame 24. The upper pillars 19 support the stationary contact members 25 to which are connected circuit conductors 2 70 and 3. The bottom pillars 20 have the contact blades 18 pivoted thereon. To the lower pillars 20 are attached conductors 26 and 27 which lead to the terminals 28 and 29 of the oil circuit breakers 7, 8 and 9. 75

When the blades 18 of the disconnecting switches are fully opened, they are electrically connected together by the engagement of the front end of each blade with jaws 30 on the rear end of the next blade of the 80 series, except that the last blade of each series is connected to the ground through a grounding contact member 31, thereby establishing a permanent ground, so long as the disconnecting switches remain in that 85 position.

Bell crank lever 14 may be operated by an electro-magnet 32 which receives its current from a transformer 34 through an auxiliary circuit 33. In case an overload occurs 90 on the circuit 2, the tripping coil 38 of the circuit breakers will be energized to permit the breakers to open in the usual manner, an electro-magnet 35 will be sufficiently energized to withdraw the catch 36 and allow the spring 37 to open the disconnecting switches, provided the circuit of the magnet 95 is closed.

In order that the disconnecting switches may be prevented from opening until after the circuit-breakers have opened, we provide the breaker mechanism with the rod 15 with a stop 40 on it, which is engaged by the upper end of the rod 39 to prevent movement of the rod 15 until the rod 39 105 has moved downwardly out of its path. All blades 18 operate in a direction which is parallel to the frames 21, 22 and 23.

2

We do not limit our invention to this particular construction, since it is equally applicable to any device requiring a disconnecting switch which will ground the circuit upon being disconnected from the source of power.

We claim as our invention:

1. In an electrical circuit, the combination with a circuit breaker, of a disconnecting switch, for electrically isolating said circuit breaker, and means coöperating with the said switch for grounding both poles of the circuit breaker when the same is isolated.
2. In an electrical circuit, the combination with a circuit breaker, of pillar-type disconnecting switches for electrically disconnecting said circuit breaker, and means coöperating with the said switches for grounding both poles of the circuit breaker when it is disconnected.
3. In an electrical circuit, the combination with a circuit breaker, of pillar-type disconnecting switches, means for operating said switches manually to disconnect said circuit breaker electrically from said circuit, and means coöperating with said switches to ground both sides of said circuit breaker.
4. In an electrical circuit, the combination with a circuit breaker, of pillar-type disconnecting switches, means for manually operating said switches, means for electrically operating said switches, and means coöperating with said switches to ground both sides of said circuit breaker.
5. In an electrical circuit, the combination with a circuit breaker, of disconnecting switches having blades pivoted to swing in the same plane, a plurality of rods and bell crank levers for manually operating said switches, means for electrically operating said switches, means for tripping said switches automatically under abnormal operating conditions, means for interlocking said breakers and said disconnecting switches, and means coöperating with said switches to ground both sides of the circuit breaker.
6. In an electrical circuit, the combination with oil circuit breakers, of pillar-type disconnecting switches having blades pivoted to swing in the same plane, a plurality of rods and bell crank levers for manually operating said switches, an electro-magnet for operating said plurality of rods and bell crank levers, means for tripping said switches automatically under abnormal operating conditions, means for interlocking said circuit breakers and said switches, and means coöperating with said switches to ground both sides of said circuit breakers.
7. In an electrical circuit, the combination with oil circuit breakers, of pillar-type disconnecting switches having blades pivoted to swing in the same plane, a plurality
8. In an electrical circuit, the combination with oil circuit breakers, of pillar-type disconnecting switches having blades pivoted to swing in the same plane, a plurality of rods and bell crank levers for manually operating said switches, an electro-magnet for operating said rods and bell crank levers, a catch, an electromagnet trip coil for actuating said catch to release said switch blades under abnormal current conditions, a spring to open said switch blades, means for interlocking said circuit breakers and said switches, and means coöperating with said switches to ground both sides of said breakers.
9. In a switching device, the combination with a plurality of terminals, of pivotally mounted blades for connecting said terminals electrically, and contact jaws mounted on the corresponding ends of the said blades for mechanically connecting the blades together and for electrically connecting the same to ground when in their full open positions.
10. In an electrical circuit, the combination with a circuit interrupter and disconnecting switches therefor, of means coöperating with the said switches for grounding both sides of the circuit interrupter when it is opened.
11. A switching device comprising a plurality of knife-blade members pivotally mounted to turn in the same plane and having contact jaws thereon to electrically connect them together when in their normally open positions.
12. A switching device comprising a circuit interrupter, a plurality of switches and means for grounding both poles of the circuit interrupter when the switches are opened.
13. In an electric circuit, the combination with a circuit interrupter and disconnecting switches, of means for opening the said switches when the circuit interrupter is tripped, and means for so electrically and mechanically connecting the switches that both poles of the said circuit are grounded when the said switches are in their open positions.
14. A switching device comprising a plurality of knife-blade members, coöperating stationary contact members therefor, and contact jaws on the ends of the knife-blade members for electrically connecting the said

- knife blade members together when they are in their open positions.
15. A switching device comprising a plurality of stationary contact members, a plurality of knife-blade members for engaging the same, said knife-blade members being pivotally mounted in the same plane and having contact jaws thereon for electrically and mechanically connecting the said knife-blade members together when in their extreme open positions.
16. A switching device comprising a plurality of knife-blade members that are pivotally mounted in the same plane, and having contact jaws on corresponding ends thereof for mechanically connecting the said knife-blade members together and for electrically connecting them to the ground when in their open positions.
- 20 17. A switching device comprising a plurality of knife-blade members, some of which are provided with contact jaws on one end thereof, each of the said jaws being adapted to receive one of the knife-blade members when the same are in their open positions.
- 25 18. A switching device comprising a plurality of knife-blade members, coöoperating

stationary contact members therefor, means for simultaneously operating said knife-blade members, and contact members on corresponding ends of the knife-blade members for engaging adjacent knife-blade members to the same when in their open positions.

19. A switching device comprising a plurality of knife-blade switches, a circuit interrupter, and means for grounding both poles of the circuit interrupter when the knife-blade switches are opened.

20. A switching device comprising a plurality of knife-blade switches, a circuit interrupter, means for grounding both poles of the circuit interrupter when the knife-blade switches are opened, and means for preventing the opening of the said knife-blade switches until the circuit interrupter is opened.

In testimony whereof, we have hereunto subscribed our names this 25th day of April, 1913.

STEPHEN Q. HAYES.
CHARLES McL. MOSS.
